US00D618617S

(12) **United States Design Patent**
Lee

(10) **Patent No.:** US D618,617 S
(45) **Date of Patent:** ** *Jun. 29, 2010

(54) **THREE WAY ELECTRICAL PLUG**

(75) Inventor: **Dominic Lee**, Hong Kong (CN)

(73) Assignee: **Multiway Industries (HK) Ltd.**, Tsuen Wan (HK)

(**) Term: **14 Years**

(21) Appl. No.: **29/313,368**

(22) Filed: **Dec. 30, 2008**

(51) LOC (9) Cl. **13-03**

(52) U.S. Cl. **D13/137.2**

(58) **Field of Classification Search** .. D13/137.1–139.8,

(57) **CLAIM**

The ornamental design for a three way electrical plug, as shown and described.

DESCRIPTION

FIG. 1 presents a pictorial view of my new three way electrical plug design.

FIG. 2 presents a top plan view of the three way electrical plug as illustrated in FIG. 1.

FIG. 3 presents a bottom pictorial view of the three way electrical plug as illustrated in FIG. 1.

FIG. 4 presents a bottom view of the three way electrical plug design as illustrated in FIG. 1.

FIG. 5 presents a front elevational view of the three way electrical plug design as illustrated in FIG. 1.

FIG. 6 presents a rear elevational view of the three way electrical plug as illustrated in FIG. 1; and,

FIG. 7 presents a left side elevational view of the three way electrical plug as illustrated in FIG. 1.

The right side elevational view of the three way electrical plug illustrated in FIG. 1 is a reverse view of FIG. 7.

The broken lines in the drawings are for illustrative purposes only and form no part of the claimed design.

1 Claim, 7 Drawing Sheets
